(57) **CLAIM**

The ornamental design for an imitation marble slab, as shown and described.

DESCRIPTION

The patent or application file contains at least one drawing executed in color. Copies of this patent or patent application publication with color drawing(s) will be provided by the Office upon request and payment of the necessary fee.

The sole FIGURE is a top plan view of an imitation marble slab showing our new design.

In the sole FIGURE, the broken lines represent portions of the article which form no part of the claimed design.
